DESIGN FOR A LIGHTING FIXTURE OR SIMILAR ARTICLE

Lemuel L. Stewart, Elkhart, Ind., assignor to The Adlake Company, a corporation of Illinois

Application November 24, 1937, Serial No. 73,178

Term of patent 14 years

To all whom it may concern:

Be it known that I, Lemuel L. Stewart, a citizen of the United States of America, and a resident of Elkhart, county of Elkhart and State of Indiana, have invented a new, original, and ornamental Design for a Lighting Fixture or Similar Article, of which the following is a specification, reference being had to the accompanying drawing, forming a part thereof, wherein

Fig. 1 is a perspective view of a lighting fix-ture or similar article showing my design; and

Fig. 2 is a sectional view taken through the center of the fixture.

The principal and dominating features of my design are shown in full line.

I claim:—

The ornamental design for a lighting fixture or similar article, substantially as shown and described.

LEMUEL L. STEWART.
